W. H. W. HAMILTON

RAZOR

Filed March 17, 1923

UNITED STATES PATENT OFFICE.

WILLIAM H. W. HAMILTON, OF BUFFALO, NEW YORK, ASSIGNOR TO HAMILTON TRIPLEX RAZOR CO. INC., OF BUFFALO, NEW YORK, A CORPORATION OF DELAWARE.

RAZOR.

Application filed March 17, 1923. Serial No. 625,730.

To all whom it may concern:

Be it known that I, WILLIAM H. W. HAMILTON, a citizen of the United States, residing at Buffalo, in the county of Erie 5 and State of New York, have invented certain new and useful Improvements in Razors, of which the following is a specification.

The object of this invention is to provide 10 an improved razor, which with a minimum amount of alteration instantly meets the demands of those who prefer the old and well-known types of razors, as well as those who prefer the later developed types of the so-called "safety" razors.

Another object is to provide an implement 15 of this type which embodies the utmost simplicity of construction, and departs as little as necessary from the long established characteristic shape of the ordinary razor, in fact comprising only three pivotally mounted parts, namely, the blade holder, the horn, and the guard, the first two of which are employed when the device is used as an ordinary 20 razor, and the three being operatively associated when the use is that of a so-called safety razor.

Persons using razors, generally speaking, 25 are of two principal classes, those preferring the ordinary and those preferring the safety razors, but there are countless numbers who would like in a single device to have an ordinary razor with its accustomed shape when such is preferred, to have a safety razor 30 when such suits their fancy, to have a safety razor in the shape of the ordinary to which long use has made them partial, to have in such a razor a construction permitting the stropping of the blade exactly as with ordinary razors, and yet to find a provision for 35 quickly removing a used and substituting in lieu thereof a fully sharpened blade.

The present invention therefore has for 40 an object the provision of each and every of these characteristics, so united and arranged to co-operate in such manner that the resulting device will meet the objections and fulfill the requirements of all. Simultaneously it will be found that the device possesses a simplicity and configuration which 45 make it most attractive and which add nothing to the cost of manufacture.

With these and other objects in view, the present invention comprises further novel de-

tails of construction hereinafter fully brought 55 out in the following description, when read in conjunction with the accompanying drawings, in which Fig. 1 is a plan view of the device arranged for use as an ordinary razor, without the guard operatively positioned with respect to the blade; Fig. 2 is a similar view of the device arranged to be used as a safety razor, with the guard positioned to permit right-handed use of the 60 razor; Fig. 3 is a view similar to Fig. 2, except that the guard is arranged for a left-handed use of the razor; Fig. 4 is a fragmentary view showing a portion of the device in use when operatively associated with a strop during the process of sharpening the 65 blade; Fig. 5 is a transverse section on the line 5—5 of Fig. 1; Fig. 6 is a transverse section on the line 6—6 of Fig. 2; Fig. 7 is a transverse section on the line 7—7 of Fig. 70 75 3; Fig. 8 is a fragmentary longitudinal section on the line 8—8 of Fig. 2; Fig. 9 is a transverse section on the line 9—9 of Fig. 4; and Fig. 10 is a front elevation of the razor 80 supporting and guard portions of the device.

Referring to the drawings, a blade 1, having a suitably enlarged stiffened backing 2 is shown as longitudinally removably positioned slidably in a holder comprising oppositely positioned substantially parallel 85 sides 3, which are connected by means of a resilient mid-section 4, adapted by reason of its resiliency to maintain the sides of the holder yieldingly in frictional contact with the backing 2 of the blade. 90

The razor supporting portion proper terminates in one direction in a hollow bifurcated shank 5, comprising a pair of spaced arms 6 which converge towards each other to the point at which they are hingedly mounted upon a pivot 7, which secures therebetween and to the opposite sides 8 a bifurcated horn or handle 9 of any well known shape and construction, said arms 6 being spaced apart by means of a bushing 10, 95 while beyond the point of pivotal connection with the horn they are narrowed and curved in the usual manner to provide a suitable finger-gripping extension 11.

Pivotedly carried by the bushing 10 is the shank portion 12 of a guard member 13, provided upon one lateral edge portion with longitudinally spaced comb-teeth 14, while

the opposite end portion 14^a of said guard member is tapered and curved so as to be housed when in one position within and between the oppositely positioned finger-gripping extensions of the blade-supporting member.

Referring to Fig. 1, the guard is shown as being oscillated into a sheltered position between the opposite sides of the horn 9, so that the relatively thin blade and its holder extend freely and operatively with respect to said horn exactly as in the case of the ordinary razor, for use by those who are either right or left handed, and the blade being sharpened upon a strop 15 in the usual manner as illustrated in Fig. 4.

Another party, however, or in fact the same person who uses the device as an ordinary razor may desire to use the blade with its guard operatively positioned with respect thereto, in which case the guard is oscillated from within the horn and into either of the positions shown in Figs. 2 and 3, the difference being that the former permits the use of the guarded blade by one accustomed to a right-handed use of articles, while the latter arrangement adapts the guarded or safety razor arrangement for use by persons who handle articles left-handedly.

It will be noted that the free end portion of the guard 13 is provided upon its laterally opposite surfaces with slender and relatively shallow hook extensions 16, one of which is adapted to surround and slidably grip the adjacent end portion of the blade when the guard is in either of the positions shown in Figs. 2 and 3, thus insuring a complete unitary relationship at all times between the guard and blade as long as the device is intended to be used as a so-called safety razor.

By referring to Fig. 10, it will be clearly seen how the diverging relationship of the sides 6 of the shank 5 permit the guard to be oscillated upon the bushing 10 transversely of the plane of the blade, so that no flexing of either guard, blade, or blade-holder is required in order to transform the guard from one side of the blade to the other, or vice versa. Furthermore, after a given blade has been used after repeated stropping and even honing in the usual manner, it is perfectly feasible to slide the used blade from its holder and to replace it by a new sharpened blade, which may then be used for a considerable period exactly as its predecessor before requiring replacement.

Having thus described my invention, what I claim and desire to protect by Letters Patent of the United States is:—

1. A razor, comprising a holder adapted to receive and support a blade longitudinally and in the transversely central portion thereof, said holder having a hollow shank, and a guard for said blade carried by a shank pivotally supported within said hollow

shank and movable transversely therein, to position the guard upon either side of the blade at will.

2. A razor, comprising a holder adapted to support a blade transversely central thereof, said holder having a hollow shank tapering towards its opposite end, and a guard carried by a shank in turn pivotally connected adjacent to and within the said first shank, said second shank being oscillatable with respect to the first shank about its pivotal connection therewith, and angularly movable upon the pivot transversely of the first shank to co-operate with either of the opposite sides of a blade within the holder. 80

3. A razor, comprising a blade holder, a guard pivotally connected therewith, and a handle having a recess and pivotally connected with said holder and said guard, said guard being adapted to be positioned within the recess of the handle or in operative relation with either side of a blade carried by the holder. 85

4. A razor, comprising a blade holder, a guard pivotally connected therewith, said guard being provided with means to engage a blade upon either side thereof, and a hollowed handle pivotally connected with said holder and said guard, said guard being adapted to remain at will within said handle 95 to provide an unguarded blade, or to be oscillated towards either of the transversely opposite sides of a blade carried by said holder.

5. A razor, comprising a blade holder, a blade removably carried by said holder, a guard, and a recessed handle both pivotally connected with said holder, said guard being adapted to enter and remain within the recess of the handle while the blade is used unguarded, or to be oscillated towards the holder and positioned upon either of the transversely opposite sides of the blade while the guarded blade is used either right- or left-handedly. 105

6. A razor, comprising a blade holder, a blade removably carried by said holder, a guard, and a recessed handle both pivotally connected with said holder, said guard being adapted to enter and remain within the recess of the handle while the blade is used 110 unguarded, or to be oscillated towards the holder and positioned upon either of the transversely opposite sides of the blade while the guarded blade is used either right- or left-handedly, said guard being provided upon its opposite sides at its free end with under-cut lugs, operative to engage the adjacent edge portion of the blade, to prevent transverse separation of the guard from the blade while in operative relationship. 115

7. A razor, comprising a blade holder, a blade removably carried by said holder, a guard, and a recessed handle both pivotally connected with said holder, said guard being adapted to enter and remain within the 120

recess of the handle while the blade is used unguarded, or to be oscillated towards the holder and positioned upon either of the transversely opposite sides of the blade while 5 the guarded blade is used either right- or left-handedly, said guard adapted to be shifted from one to the other side of the blade, first by relative oscillation about their pivotal connection until they are disengaged, then 10 by relative transverse movement upon their pivotal connection until they are again operatively engaged.

8. A razor, comprising a blade holder, and a guard pivotally connected therewith, said 15 guard being provided with oppositely posi-

tioned blade-engaging means, operative to maintain the guard in normal operative relation with and upon either side selectively of a blade carried by the holder, said guard adapted to be shifted from one to the other 20 side of the blade, first by relative oscillation about their pivotal connection until they are disengaged, then by relative transverse movement upon their pivotal connection, and then by relative oscillation about their pivotal 25 connection until they are again operatively engaged.

In testimony whereof I have affixed my signature.

WILLIAM H. W. HAMILTON.
